UNITED STATES PATENT OFFICE.

LEWIS AUGUSTUS ASPINWALL, OF JACKSON, MICHIGAN, ASSIGNOR TO ASPINWALL MANUFACTURING COMPANY, OF JACKSON, MICHIGAN, A CORPORATION OF MICHIGAN.

POTATO-PLANTER.

SPECIFICATION forming part of Letters Patent No. 772,202, dated October 11, 1904.

Application filed April 28, 1904. Serial No. 205,274. (No model.)

To all whom it may concern:

Be it known that I, LEWIS AUGUSTUS ASPINWALL, a citizen of the United States, residing at Jackson, in the county of Jackson and State 5 of Michigan, have invented an Improvement in Potato-Planters, of which the following is a specification.

My present invention relates to improvements upon the potato-planter devices shown 10 and described in Letters Patent granted to me May 8, 1883, No. 276,994; May 25, 1886, No. 342,491, and September 23, 1902, No. 709,660, with the object of overcoming the difficulties existing in the earlier devices and 15 providing a more efficient mechanism.

In my Patents Nos. 276,994 and 342,491 there were devices assisting in engaging potatoes too large and heavy to be alone held by the prongs upon which they were impaled in the 20 operation of the machine; but these devices were more or less inefficient because of their form and the fact that their pivotal connection was not in the line of their length; which fact caused them to swing away too rapidly and lessened the chances of their holding the 25 large potatoes in place.

In my present improvement and in connection with the devices of my Patent No. 709,660 I employ an extension to the pivoted plate 30 previously used with a disk roller which controls the gravity position of the blade on the upward movement through the concaves, also a thumb-piece or gravity-clamp pivoted in the line of its length and grooved in the part coming next to the extension and the disk roller 35 and preferably on the end. As shown in my former patent, the disk roller serves to prevent toggling of the potatoes while passing up the V-shaped concaves, which causes a miss 40 or failure to plant. When two potatoes of a certain size fall in the concaves, the disk roller turns sufficiently to allow but one to adjust itself properly against the pivoted plate which supports the roller. In the upward movement 45 of the arm carrying these parts the thumb-piece or gravity-clamp hangs toward the pivoted plate in such a position that if the potato impaled upon the prongs is large it comes

against the disk roller in the jaw of the pivoted plate and against the thumb-piece or 50 gravity-clamp, where it is held until the pivoted plate is tripped by the cam-plate and the clamp released. If the potato is small, it is impaled upon and held by the prongs only and when the arm swings over the thumb-piece or gravity-clamp falls away, performing 55 no function.

In the drawings, Figure 1 is an elevation representing my improvements and a section through parts of the potato-planter. Fig. 2 60 is an elevation of an arm carrying the pivoted plate and its extension and the thumb-piece or gravity-clamp of my present improvement and a section of the axle and sleeve of the potato-planter, the same being in larger size. 65 Fig. 3 is a plan of the parts shown in Fig. 2 except the axle and sleeve and with the thumb-piece or gravity-clamp thrown back, and Fig. 4 is a cross-section at about the center of the gravity-clamp. 70

a represents the frame or a part thereof of a potato-planter; *b*, the magazine or potato-holder; *c*, the slotted concaves; *d*, the axle; *e*, the sleeve; *f*, a disk upon the sleeve; *g*, a cam-plate on the frame. 75

3 represents bolt-holes in the disk *f*, and *4* bolts passing through said bolt-holes for securing the arms *h* in position upon the disk *f* with the forked ends thereof resting against the sleeve *e*. The parts herein just described 80 correspond with similar parts and have the same functions as similar parts described in my aforesaid patents.

The end of each arm *h* is preferably offset at *h'*, and a plate *i* is secured thereto by a 85 rivet 5, and between the offset and plate there is formed a receptacle for the pivoted plate *k* and its extension *k'*, which is connected to the parts *h'* and *i* by a pivot-pin 11. A guide-pin 12 passes through these parts and between 90 the same through a slot in the plate *k*, so that the plate *k* is free to swing with reference to the said parts an extent equal to the length or limits of the slot 8. This slot is shown by dotted lines. The pivoted plate *k* is provided 95 with a curved extension or projecting portion

k', forming a stop and also a shield for the roller 13, which roller is mounted in the jaw-frame 14 on the advancing end of the plate *k*. Prongs 10 are secured to opposite faces on each arm *h* by rivets 6, the edges of the prongs being situated against the ends of the plates *i*. These prongs where they project from the edge surface of the frame *h* pass at either side of the extension *k'* and roller 13. I provide a thumb-piece or gravity-clamp *l*, connected by a pivot-pin 7 to each arm *h* adjacent to the connection of the prongs 10 with said arm *h*. This gravity-clamp *l* is grooved along the edge coming next to the roller 13 and extension *k'* and also grooved in the end thereof. It is free to swing on its pivot 7, and it is to be remarked that the pivot 7 is directly in the line of the gravity-clamp—that is, a line drawn substantially centrally and longitudinally through the said clamp will also pass through the pivot 7. Therefore a force exerted against the end of said gravity-clamp is a direct thrust.

In Fig. 1 so much of the potato-planter machine is shown as is necessary to understand the operation of the arms and the parts connected therewith, there being shown in Fig. 1 three full arms only. The uppermost of these arms, as shown in Fig. 1, carries a small potato impaled upon the prongs 10, with the potato coming between the roller 13 and the jaw-frame 14. The arm that is substantially horizontal in Fig. 1 is shown as carrying a large-sized potato, in which the potato as impaled upon the prongs 10 comes between the roller 13, the jaw-frame 14, and the end of the gravity-clamp *l* upon the side opposite to the jaw-frame, the thrust on said gravity-clamp being in the direct line of the pivot, tending to keep the gravity-clamp in position and insure the support of the large-sized potato. No potato is shown on the lowermost of the arms, Fig. 1, because the plate *k* has been tripped against the cam-plate *g* and the potato removed from the prongs and delivered, or, in other words, permitted to fall by gravity to the earth.

The arm, Fig. 1, that is shown as substantially horizontal is about to be tripped by its back-end coming against the cam-plate *g*. This will cause a movement of the plate *k* and roller 13 to push the potato off the prongs 10. The gravity-clamp will thus be released and will fall until it occupies a vertical position. The gravity-clamp connected to the uppermost arm in Fig. 1 is shown as hanging down against the arm. It will swing with the movement of this arm until it occupies the position shown in connection with the lowermost arm, and as the arm, with the plates and connected portions, goes through the concaves and the hinge-plate *k* is swung so as to cause a potato to be impaled upon the prongs the gravity-clamp *l* will engage the potato if the same be of large size; but if of small size

the potato will not reach to the end of the thumb-piece or clamp, which will perform its movements by gravity, as heretofore described. The grooved portion of the gravity-clamp coming next to the extension *k'* of the pivoted plate permits the said gravity-clamp at its end to come into direct contact with the free ends of the prongs 10, so as to take a straight line and positive hold upon potatoes of large size. The grooved end of the gravity-clamp assists in holding the potatoes in place, because thereby it is possible to engage the potato not only at two points, but at each side of an imaginary vertical and central plane through the coacting devices.

I claim as my invention—

1. In a potato-planter, the combination with a revoluble arm, an axle, and means for connecting the same to and supporting the same from the axle, a swinging pivoted plate and means for impaling potatoes, of a gravity-clamp pivoted to said arm in the line of its length and adapted to engage potatoes of a large size in such a manner that the thrust upon the gravity-clamp is in a straight line to the pivot.

2. In a potato-planter, the combination with a revoluble arm, an axle and means for connecting the same to and supporting the same from the axle, a swinging pivoted plate and means for impaling potatoes, of a gravity-clamp pivoted to said arm, and grooved at the end, the pivot of the said gravity-clamp to the arm being in the line of its length so that when large-sized potatoes are engaged thereby the thrust is approximately in the line of the arm to the pivot.

3. In a potato-planter, the combination with an axle, a disk mounted thereon and a series of revoluble arms mounted on said disk at the free ends of each of which are spaced-apart portions forming a receptacle, of a pivoted plate having an extension and pivotally mounted between the said portions, means for limiting the swinging movement of the said plate, a roller and jaw-frame in which the roller is pivoted, said jaw-frame being mounted on the plate, prongs secured to the end of the arm and coming at each side of the arm and at opposite faces of the roller, and a gravity-clamp pivoted to said arm and adapted to swing into operative position against the prongs so that when potatoes of large size are engaged the thrust is in the line of the length of said clamp to its pivot.

4. In a potato-planter, the combination with an axle, a disk mounted thereon, and a series of revoluble arms mounted on said disk, a pivoted plate mounted between the said portions, means for limiting the swinging movement of the said plate, a roller and jaw-frame in which the roller is pivoted, prongs secured to the end of the arm and coming at each side of the arm and at opposite faces of the roller, and a gravity-clamp pivoted to said arm and adapted

to swing into operative position against the prongs, so that when potatoes of large size are engaged the thrust is in the line of the length of said clamp to its pivot, said gravity-clamp 5 being wider than the width of the arm to which it is pivoted and grooved on its end so as to present two points of bearing contact to the potato.

5. In a potato-planter, the combination with 10 an axle, a disk mounted thereon, and a series of revolute arms mounted on said disk, a plate pivotally mounted between the said portions, means for limiting the swinging movement of the said plate, a roller and jaw-frame in which 15 the roller is pivoted, said jaw-frame being mounted on said plate, prongs secured to the end of the arm and coming at each side of the arm and at opposite faces of the roller, and a gravity-clamp pivoted to said arm and adapted 20 to swing into operative position against the prongs, so that when potatoes of large size are engaged the thrust is in the line of the length of said clamp to its pivot, the said plate being provided with an extension k' in line with and 25 surrounding the base of the roller, and forming a shield to the roller.

6. In a potato-planter, the combination with an axle, a disk mounted thereon, and a series of

revolute arms mounted on said disk, a plate pivotally mounted between the said portions, 30 means for limiting the swinging movement of said plate, a roller and jaw-frame in which the roller is pivoted, said jaw-frame being mounted on said plate, prongs secured to the end of the arm and coming at each side of the arm 35 and at opposite faces of the roller, and a gravity-clamp pivoted to said arm and adapted to swing into operative position against the prongs, so that when potatoes of large size are engaged the thrust is approximately in the 40 line of the length of said clamp to its pivot, the said plate being provided with an extension k' in line with and surrounding the base of the roller and forming a shield to the roller, the gravity-clamp being of greater width 45 than the arm to which it is pivoted and grooved in its edge coming next to the plate extension so as to receive the same when in operative position and also grooved on its end so as to provide two points of bearing contact with the 50 potato.

Signed by me this 7th day of April, 1904.

LEWIS AUGUSTUS ASPINWALL.
